UNITED STATES PATENT OFFICE.

WILLIAM CHARLES STEPHENS, OF CAMBORNE, ENGLAND.

ROCK-DRILL.

SPECIFICATION forming part of Letters Patent No. 781,241, dated January 31, 1905.

Application filed October 12, 1903. Serial No. 176,686.

To all whom it may concern:

Be it known that I, WILLIAM CHARLES STEPHENS, a subject of the King of Great Britain, residing at "Endsleigh," Camborne, county of 5 Cornwall, England, have invented new and useful Improvements in Rock-Drills, of which the following is a specification.

My invention relates to rock-drills of the kind wherein the distributing-valve is controlled by air-pressure and wherein air-locks are formed in connection with the ends of the said valve. In such drills the movement of the valve is controlled by the working piston, which at certain points in its stroke uncovers 10 ports connected with the air-locks and allows the escape of the air therefrom, so that the air under pressure can move the valve in the required manner. The effective working of such a valve is dependent upon the said ports 15 being retained properly closed until definite points of the stroke are reached; but it is found in practice that as the working piston wears the said ports are not completely closed, so that the air escapes from the locks prematurely and reverses the valve before the stroke 20 of the piston is completed. As a matter of fact, as the wear proceeds the stroke of the piston becomes gradually shorter and shorter, the movements of the valve becoming more and 25 more irregular.

The object of my invention is to provide improvements whereby notwithstanding the wear of the pistons the opening and closing of the ports shall be properly controlled by 30 the pistons, and to this end I provide an arrangement of valves operated by the piston which serve to open and close the ports in the required manner without permitting air to escape prematurely from the air-locks.

40 In the accompanying drawings, Figure 1 is a longitudinal section of a drill having my improvements applied to it; and Figs. 2, 3, and 4 are sectional views showing various arrangements of valve which can be made use of.

45 *a* is the cradle of the drill; *b*, the working cylinder arranged to be traversed upon the cradle by means of the screw *c*.

d is the working piston, *e* the twist-gear, and *f* the distributing-valve, which serves for 50 admitting and exhausting the air into and

from the two ends of the working cylinder through the passages *g* *g'*. This valve *f* works in a chamber *f'*, having a passage *f''*, with which the air-supply pipe communicates. In the walls of the chamber *f'* are two grooved 55 channels *f³* *f⁴*, which are alternately brought into communication with a groove *f⁵* around the valve during its reciprocation. With the valve in the position shown in the drawings the channel *f⁴* is in communication with the 60 air-supply, which acts on a ring-shaped surface *f⁶* around the end of the piston. When the air is allowed to escape from the opposite end of the chamber *f'*, as hereinafter described, the pressure of air upon this ring-shaped space will be sufficient to push the valve over, and then the passage *f³* will be placed in communication with the air-supply, so that on the release of the air from the end 65 first referred to the valve will be again moved, 70 and so on.

h *h'* are the air-locks on the two ends of the distributing-valve, and *i* *i'* are the passages extending to the ports *j* *j'*, which have to be alternately opened and closed.

The simplest form of closure in connection with the said ports consists in the introduction into the said ports of bushings *k*, of leather or other flexible material, (with or without metallic linings, such as *l*.) which extend through the ports into contact with the piston and which as the piston wears can be pressed down more or less, so as to maintain them in contact with the said piston. I propose, however, to use in connection with these 80 bushings *k* mechanically-operated valves.

In Fig. 1 I have shown valves *m* *m'* mounted upon a double-armed lever and which as the piston reciprocates is oscillated by the contact of the piston therewith in order to alternately bring the valves into contact with the bushings. As the piston wears the bushings can be moved down toward the said valves in the same way that plain bushings working 85 without valves could be adjusted.

In the arrangement shown in Fig. 2 ball-valves *n* *n'*, working independently, are used, the said valves being held against the bushings and released in the same manner as the valves *m* *m'*.

100

When valves such as n n' are made use of, the recesses in which the balls are placed below the bushings are so shaped that the valves will be supported while the central recess in 5 the piston is passing them.

The arrangement shown in Fig. 3 is the same as that shown in Fig. 2, except that pairs of balls o o' instead of a single ball n n' are made use of.

- 10 In the arrangement shown in Fig. 4 disk valves p p' , having extension - pieces q q' , which extend into the path of the piston, are arranged in connection with seatings r r' , springs s s' being arranged around the stems 15 of the said valves for the purpose of causing them to act quickly when released by the piston.

With all the foregoing arrangements it will be understood that the valves when open will 20 project into the path of the piston sufficiently to be acted upon by the latter during its reciprocation to close the ports to the air-locks and that, as the piston wears, the bushings, in connection with the valves, can be adjusted to 25 compensate for this wear, whereby, notwithstanding that the piston wears, the ports to the air-locks may be tightly closed until the piston reaches the desired points in its stroke.

Having now particularly described and as 30certained the nature of my said invention and in what manner the same is to be performed, I declare that what I claim is—

1. In a rock-drill, the combination with a working cylinder and a reciprocating piston 35therein, of a distributing-valve casing for said cylinder provided with air-locks, and a distributing-valve in said casing, ports in the cylinder connected with passages extending to said air-locks, bushings in said ports, and 40movable valves having portions for directly engaging said bushings and wearing portions projecting into the cylinder in the path of the piston and adapted to be operated thereby, substantially as described.
- 45 2. In a rock-drill, the combination with a working cylinder and a reciprocating piston

therein, of a distributing-valve casing for said cylinder provided with air-locks, and a distributing-valve in said casing, ports in the cylinder connected with passages extending 50 to said air-locks, adjustable bushings in said ports and movable valves having portions for directly engaging said bushings and wearing portions projecting into the cylinder in the path of the piston, whereby the wear on said valves and said piston may be compensated by adjustment of said bushing, substantially as described. 55

3. In a rock-drill, the combination with a working cylinder and a reciprocating piston 60therein, of a distributing-valve casing for said cylinder provided with air-locks, and a distributing-valve in said casing, ports in the cylinder connected with passages extending to said air-locks, flexible bushings in said 65ports and movable valves having portions for directly engaging said flexible bushing and wearing portions projecting into the cylinder in the path of the piston, whereby said bushings may be forced into said ports to compensate for 70the wear on said valves and said piston, substantially as described.

4. In a rock-drill, the combination with a working cylinder and a reciprocating piston 75therein, of a distributing-valve casing for said cylinder provided with air-locks and a distributing-valve in said casing, ports in the cylinder connected with passages extending to said air-locks, flexible bushings in said 80ports, metallic linings in said bushings, movable valves having portions for directly engaging said flexible bushings and wearing portions projecting into said cylinder in the path of the piston, whereby said bushings may be forced into said ports to compensate for 85the wear on said valves and piston, substantially as described.

WILLIAM CHARLES STEPHENS.
